J. A. LANE.
WINDOW ADJUSTER AND LOCK.
APPLICATION FILED SEPT. 20, 1918.

1,297,479.

Patented Mar. 18, 1919.

INVENTOR:
James A. Lane,
by Compt. Comm.,
his Atty.

UNITED STATES PATENT OFFICE.

JAMES A. LANE, OF LOS ANGELES, CALIFORNIA.

WINDOW ADJUSTER AND LOCK.

1,297,479.

Specification of Letters Patent. Patented Mar. 18, 1919.

Application filed September 20, 1918. Serial No. 254,902.

To all whom it may concern:

Be it known that I, JAMES A. LANE, a citizen of the United States, and a resident of the city of Los Angeles, county of Los Angeles, and State of California, have invented a new and useful Improvement in Window Adjusters and Locks, of which the following is a specification.

My invention relates to devices for bowing 10 casement window sashes and the like.

With casement windows, it is customary to mount the window screens inside of the sash; and with ordinary windows, it is quite common to place the shutters outside of the 15 sash. The principal object of my invention is to provide a device whereby a casement window sash may be operated from the inside without disturbing the window screen and whereby the shutter may be operated 20 without disturbing the sash. Another principal object is to provide for the locking of the shutter or casement window sash or the like at any desired point within its range of movement. Other principal objects are 25 to make such a device as simple and cheap as practicable and to achieve advantages hereinafter appearing. The invention consists mainly in a lever operatively connected to the sash or shutter to operate the same 30 from inside the room without disturbing an intervening screen, sash or the like and provided with a locking device adapted to lock the sash at any point within its range of movement; it also consists in the arrangements and combinations of parts hereinafter 35 described. In the accompanying drawing wherein like numerals refer to like parts wherever they occur.

Figure 1 is a horizontal section taken 40 through a casement window with the sash partly open, showing an adjuster embodying my invention applied thereto; the sash being shown in closed position by the dot and dash lines, and the sill being partly broken away 45 to more clearly illustrate the invention;

Fig. 2 is an enlarged fragmentary cross section taken through the outer end of the locking bar, showing the window closed and the locking bar in a locked position, the locking bar being indicated in unlocked position 50 by the dot and dash lines;

Fig. 3 is a vertical section on the line 3—3 in Fig. 1 showing the lower part of the sash and the slidable strap which connects the 55 end of the operating lever to the guide bar;

Fig. 4 is a vertical section on the line 4—4 in Fig. 1 showing the slot and pin connection between the locking bar and slidable strap;

Fig. 5 is a vertical section through the 60 window frame on the line 5—5 in Fig. 1 showing the fulcrum pin of the operating lever and the slotted connection between the locking bar and said pin;

Fig. 6 is a side view of the inner portion 65 of the operating lever, showing the drop handle pivotally mounted thereon, in its unlocked position;

Fig. 7 is a view similar to Fig. 6 showing the drop handle in its locked position, the 70 side wall of the drop handle being broken away to more clearly illustrate the connection between the drop handle and the locking bar;

Fig. 8 is a vertical cross section through 75 the drop handle on the line 8—8 in Fig. 6;

Fig. 9 is a vertical section through the drop handle on the line 9—9 in Fig. 7 looking at the under side of the locking bar; and

Fig. 10 is a horizontal section through the 80 slidable strap which connects the locking bar to the guide bar, showing a modified form of locking bar and friction shoe.

In the accompanying drawing, my invention is illustrated as applied to a casement 85 window. In said drawing, 1 indicates the sides of the window frame, 2 indicates the window sill, 3 indicates the casement window sash pivotally mounted at one side to the side of the window frame 1 by means of hinges 4. 90

Mounted on the lower inside face of the casement sash is a horizontal guide rod or bar 5 whose body portion is spaced slightly from the inner face of the sash and whose end portions are offset and secured to the, 95 inner face of the sash by screws or otherwise. Slidably mounted on said guide bar is a loop or strap 6 which straddles said guide bar and is pivotally connected to the long arm of a lever 7 whose fulcrum is a vertically 100 extending pivot pin 8 mounted on a plate 9 which is secured to the window frame below the sill. This fulcrum is located toward the inner face of the window frame and not far from the side of the frame to which the sash is hinged. The inner or short arm of the 105 lever is bent at an obtuse angle to the outer arm and extends through a slot provided therefor in the face of the window frame.

By this arrangement, the inner end of the 110

lever 7 extends into the room so as to be accessible for manipulation of the sash without raising the screen. The inner end portion of the lever 7 is offset upwardly and has a plate 10 riveted or otherwise secured to its underside. The plate is provided with downwardly extending side flanges 11 having oppositely disposed ears or lugs 12 depending therefrom at the inner end of the plate. The inner end of the lever 7 is provided with a drop handle 13, that is, a handle or extension having a hollow head portion 14 which is pivotally mounted on the downwardly depending ears 12 of the plate by means of horizontally extending pins 15 which permit said handle portion to hang normally in a vertical position close to the window frame and to be swung into a horizontal position for manipulating the lever. By this arrangement, the handle is accessible from the interior of the room and when it is brought into a horizontal position, it constitutes an extension or elongation of the short arm of the lever and thus makes it easier to actuate the same. As the fulcrum of the lever is spaced away from the axis of the hinges of the sash, the swinging movement of the lever causes the sash also to swing on its hinges, the slidable strap that connects the end of the lever to the guide bar accommodating itself to this movement by sliding on the guide bar.

In order to provide for the locking of the casement window at any point in its range, a frictional locking bar 16 is provided. This frictional locking bar is of the same general shape as the actuating lever 7 and mounted immediately below the lever. For the purpose of mounting the locking bar 16 it is provided with two elongated slots 17 and 18. The slot 17 is disposed parallel with the short arm of the locking bar and actuating lever and the other slot 18 is disposed obliquely to the long arm of the lever. The fulcrum pin 8 of the lever 7 passes through the slot 17 and a pin 20 specially provided for the purpose on the lever near its outer end extends through the other slot 18. By this arrangement, the locking bar is made movable obliquely relatively to the lever, the movement being partly longitudinal of the long arm of the lever and partly transversely thereto. The movement thus provided for is effected by means of the drop handle of the lever as follows: The inner end of the locking bar has a downwardly extending portion 22 that is provided with a vertical slot 23 through which a horizontally disposed pin 24 passes. This pin extends across the hollow head 14 of the drop handle 13 and is riveted or otherwise secured to the side walls of the hollow head 14. The slot 23 in the downwardly projecting portion 27 of the locking bar is disposed tangentially or eccentrically with reference to the pivot of

the drop handle and thus produces a cam action that is effective to move the locking bar to and from the pivot of said handle and obliquely with reference to the outer arm of the lever, the elongated slots 17 and 18 in said locking bar co-operating with the fulcrum pin 8 and the pin 20 on the outer end of the actuating lever to permit and control the direction of said movement.

Near its outer end, the locking bar 16 is rounded off on its inner face as at 25. Located in the slidable loop or strap 6 between the top and bottom flanges thereof is a clamping block or friction shoe 26 having a rounded portion 27. This friction shoe is located between the rounded off portion 25 of the locking bar and the guide rod or bar 5 secured to the inner face of the casement window sash 3, and is secured in place between the flanges of the slidable loop by means of a pin 28, said pin being slightly smaller than the hole provided therefor in the block so as to enable said block to move slightly relative to said pin. The curvature of the rounded off portion 25 of the locking bar is such that when the locking bar is in the position corresponding to the horizontal position of the drop handle, there is sufficient clearance between the rounded portion 27 of the clamping block 26 and the edge of the rounded off portion 25 on the inner face of the locking bar to permit the connecting loop to slide freely on the guide rod; and when the drop handle is turned into a vertical position, the edge of the locking bar is forced against the rounded portion of the clamping block and thereby causes the clamping block and loop to bind firmly against the guide rod and lock them securely to the guide rod. By this arrangement, the movement of the drop handle will cause the slidable loop and clamping block to loosen or tighten their grip on the guide rod at any and all positions within the range of movement of the casement sash.

The inner margin of the outer end of the long arm of the locking bar is provided with an extending finger 29, preferably beveled on its outer face; and the window frame is provided with a member for co-operating therewith. As illustrated in the drawing, this co-operating member is a plate 30 secured to the window sill and having an upright portion 31 opposite the extending finger of said locking arm. This upright portion is so positioned that when the locking arm is in its unlocked position, the extending finger thereof will barely clear said member and so that, when the locking bar is in its forward position, the finger thereon will overlap or pass beyond said member and constitute therewith a lock.

In the modification shown in Fig. 10 of the drawing, the inner face of the locking bar 32 adjacent the rounded portion of the

friction shoe 33 is shown beveled as at 34 instead of being rounded so as to coöperate with the rounded portion of the friction shoe. The friction shoe in this figure is 5 loosely pinned in place between the flanges of the slidable loop so as to be forced against the guide rod when the locking bar is thrown forward. It will also be noticed in connection with this figure that the locking bar has 10 no finger extension. The finger being necessary only to prevent the window sash being forced open from the outside.

Obviously the construction hereinbefore described admits of considerable modification 15 without departing from my invention and I do not wish to be restricted to the details thereof.

What I claim is:

1. The combination with a window frame 20 having a sash or the like hinged thereto at one side of an adjuster therefor comprising a horizontal guide-rod mounted on said sash, a lever pivotally mounted on the bottom portion of said frame, one arm of said lever 25 being slidably connected to said guide-rod so as to be slidable thereon and the other arm of said lever having a handle extending inside of said frame for manipulating said lever, and a locking arm associated with 30 said lever and operable to clamp the connection between said lever and said guide-rod.

2. The combination with a window frame having a sash or the like hinged thereto at 35 one side of an adjuster therefor comprising a horizontal guide-rod mounted on said sash, a lever pivotally mounted on the bottom portion of said frame, one arm of said lever being slidably connected to said guide-rod so as to be slidable thereon and the other 40 arm of said lever having a handle extending inside of said frame for manipulating said lever, and a locking arm associated with said lever and operable to clamp the connection between said lever and said guide-rod, said handle being pivoted to swing vertically and having an eccentric portion arranged to coöperate with said locking arm to move the same.

3. The combination with a window frame 50 having a sash or the like hinged thereto at one side of an adjuster therefor comprising a horizontal guide-rod mounted on said sash, a lever, which has one end operatively slidably connected to said guide-rod and its 55 other end in position to be actuated from within the room, and means for locking the connection between said lever and said guide-rod, said means comprising a locking member movably mounted on said lever and 60 having cam slots and said lever having pins extending through said slots, and means for moving said locking member independently of the body portion of said lever.

4. The combination with a window frame 65 having a sash or the like hinged thereto at

one side of an adjuster therefor comprising a horizontal guide-rod mounted on said sash, a lever, which has one end operatively slidably connected to said guide-rod and its other end in position to be actuated from 70 within the room, and means for locking the connection between said lever and said guide-rod, said means comprising a locking member movably mounted on said lever and having cam slots and said lever having pins extending through said slots, and means for moving said locking member independently 75 of the body portion of said lever, said means comprising a drop handle pivotally mounted on the inner end of said lever having an eccentric portion arranged to bear against a coöperating part of said locking member.

5. The combination with a window frame having a sash or the like hinged thereto at one side of an adjuster therefor comprising 80 a horizontal guide-rod mounted on said sash, a lever having one end slidably linked to said guide-rod and its other end manually operable, a bar obliquely slidably mounted on said lever, and means for moving said 85 slide-bar to frictionally hold the link in any adjusted position on said guide-rod, said means comprising a handle pivotally mounted on the inner end of said lever and having an eccentric portion arranged to coöperate 90 with said slide-bar.

6. The combination with a window frame having a sash or the like hinged thereto at one side of an adjuster therefor comprising 95 a horizontal guide-rod mounted on said sash, a lever pivotally mounted on the bottom portion of said frame, the outer arm of said lever being provided with a connecting member that is slidably mounted on said 100 guide-rod and the other arm of said lever having a handle extending inside of the room for manipulating said lever, a slide-bar movable with said lever but movable obliquely also relative to said lever and independently thereof, a portion of said slide-bar 105 near the outer end of said lever being in position to frictionally bind said connecting member against said guide-rod.

7. The combination with a window frame having a sash or the like hinged thereto at 110 one side of an adjuster therefor comprising a horizontal guide-rod mounted on said sash, a lever having one end slidably linked to said guide-rod and its other end manually operable, a bar obliquely slidably mounted 115 on said lever, and means for moving said slide-bar to frictionally hold the link in any adjusted position on said guide-rod.

8. The combination with a frame having a member hinged thereto of an adjuster 120 therefor comprising a guide-rod mounted on said hinged member, a lever having one end slidably linked to said guide-rod and its other end manually operable, a bar obliquely 125 mounted on said lever, and means 130

for moving said slide bar to frictionally hold the link in any adjusted position on said guide-rod.

9. An adjuster comprising a guide-rod, a lever having one arm slidably connected to said guide-rod and having its other arm arranged for manipulation, and a locking bar movably mounted on said lever and operable to clamp the connection between said lever and said guide-rod.

10. An adjuster comprising a guide-rod, a lever having one arm slidably connected to said guide-rod and having its other arm arranged for manipulation, said lever having a fulcrum pin and a pin near its connection to said guide-rod, and a locking bar having oblique slots fitting over said pins, and

means for moving said locking-bar to bind said lever to said guide-rod.

11. An adjuster comprising a guide-rod, a lever having one arm slidably connected to said guide-rod and having its other end provided with a manipulating handle pivoted thereto, a fulcrum pin for said lever and a pin on said lever near its connection to the guide-rod and a locking bar having oblique slots fitting over said pins and operatively connected to said pivoted handle to be actuated thereby to bind the connection between said lever and said guide-rod.

Signed at Los Angeles, Cal., this 11th day of Sept., 1918.

JAMES A. LANE.
